LENS UNIT FOR AIRPORT RUNWAY SIGNAL LIGHTS

Robert I. Nagel, Skokie, Ill., assignor to Elastic Stop
Nut Corporation of America, Union, N.J., a corpora-
tion of New Jersey

Filed May 9, 1958, Ser. No. 50,826

Term of patent 14 years

(Cl. D48—16)

FIG.1

FIG.2

Des. 188,435

PAGE 2

FIG.3

FIG.4

FIG. 5

FIG. 6

Fig. 1 is an elevation of lens unit for airport runway signal lights embodying my new design;

Fig. 2 is a top view thereof;

Fig. 3 is an elevational view thereof;

Fig. 4 is a bottom view thereof;

Fig. 5 is a sectional view taken on line 5—5 of Fig. 2; and

Fig. 6 is a perspective view thereof.

I claim:

The ornamental design for a lens unit for airport runway signal lights, as shown.
